Term of patent 14 years

(Cl. D58—2)

FIG. 1.

FIG. 2.

FIG. 1 is a top plan view of a package of loose leaf notebook filler paper embodying my new design; and FIG. 2 is an end elevational view thereof.

The bottom and sides of said package are substantially plain. The end not shown is substantially the same as the end shown in FIG. 2 except as indicated in FIG. 1.

I claim:

The ornamental design for a package of loose leaf notebook filler paper, substantially as shown and described.
